Assistant Examiner — Kaitlan Walker

CLAIM

The ornamental design for a trigger lock, as shown and described.

DESCRIPTION

FIG. 1 is an isometric view of trigger lock showing my new design;

FIG. 2 is a front elevational view thereof of FIG. 1;

FIG. 3 is a rear elevational view thereof of FIG. 1;

FIG. 4 is a right elevational view thereof of FIG. 1;

FIG. 5 is a left side elevational view thereof of FIG. 1;

FIG. 6 is a top plan view thereof of FIG. 1; and,

FIG. 7 is a bottom plan view of thereof of FIG. 1.

The broken lines are included for the purpose of illustrating features of the trigger lock that form no part of the claimed design.

1 Claim, 5 Drawing Sheets
